FIG. 1.

FIG. 2.

FIG. 3.

FIG. 4.

FIG. 5.

FIG. 6.

INVENTOR:

Erwin R. Stoeckle

UNITED STATES PATENT OFFICE.

ERWIN R. STOEKLE, OF MILWAUKEE, WISCONSIN.

RHEOSTAT.

Application filed May 5, 1924. Serial No. 711,198.

To all whom it may concern:

Be it known that I, ERWIN R. STOEKLE, a citizen of the United States, residing at Milwaukee, in the county of Milwaukee and State of Wisconsin, have invented new and useful Improvements in Rheostats, of which the following is a full, clear, concise, and exact description, reference being had to the accompanying drawings, forming a part of this specification.

This invention relates to improvements in the construction of electrical resistance devices particularly rheostats for the control of an electric current.

In rheostats in which the variably contacting element bears directly on the turns of wire of the electrical resistor a common difficulty arises in the loosening of these turns of wire upon their support, due to the differential expansion of the wire and its support caused by the heat generated by the electrical current. This loosening of the turns of the resistor causes them to move and touch one another when the contacting element is moved, thereby causing erratic changes in the resistance.

One object of this invention is to provide a resistance device in which the wire constituting the resistance element is firmly held in position.

Another object is to provide a rheostat structure in which the wire elements constituting the resistor are firmly clamped between electrically insulating and slightly yielding surfaces, so that each element will be somewhat embedded in said insulating surfaces, and thus held in insulated relation with its neighboring elements.

Another purpose of this invention is to provide an effective and easily assembled structure for accomplishing the above objects.

Another object is to provide a rheostat structure in which effective cooling of the resistor is accomplished by conduction and radiation of the generated heat.

Other objects and novel features of this improved resistance device will be apparent from the following description and drawings of Figs. 1 to 6.

Figure 1 shows a perspective view of a preferred form of the resistance device.

Figure 2 shows a cross sectional view of the structure of Fig. 1.

Figures 3 and 4 show respectively the

method of establishing contact with the end of the resistor and with the metal cups constituting the members for retaining the resistor.

Figure 5 shows an enlarged horizontal section of a portion of the resistor element, its associated insulation, and retaining members.

Figure 6 shows another structure employing the same methods of firmly retaining the resistor as are disclosed in Figs. 1 and 2.

Referring to the Figs. 1 and 2, the resistance element 1 is retained in the annular groove formed by the external cylindrical shell or cup 2 and the internal cylindrical member 3. The resistor is insulated from these metal cups by means of the insulating strips 5 and 6 and the insulating washer 4. These strips are preferably of a slightly yielding material such as asbestos paper or the like so that the wire of the resistance element may become partially embedded therein.

The external and internal cylindrical members are shown as made of metal although either or both may obviously be made of some insulating material in which case the corresponding insulating strips may be omitted. A good alternative construction is to make the external shell of metal and the internal member a cylinder of moulded insulating material.

The terminal posts 7 and 8, shown in Figs. 1, 3 and 4 serve to establish electrical connection with one end of the wire of the resistor as shown in Fig. 3, and also for connecting to the metal cups as shown in Fig. 4. In Fig. 3 the terminal screw 7 is shown riveted at 26 to the insulating core 25 upon which the resistance wire 28 is wound. The end of this wire is shown bound under the nut 27. In Fig. 4 the terminal 8 is shown with a threaded portion extending through the metal cup 2 and fastened thereto by means of a nut 29.

Referring again to the Fig. 2 the threaded hollow bushing 9 extends substantially centrally through the metal cups. This bushing in cooperation with the shoulder 10 and the nut 11 serves to hold the metal cup 3 firmly within the resistor. The inner cylindrical surface of the cup 2 and the outer cylindrical surface of the cup 3 may be formed slightly conical as shown, so that as these cups are drawn together by means

of the nut 11 a very considerable radial pressure will be exerted upon the resistor and the adjacent insulating strips 5 and 6. This will result in partially embedding the wires of the resistor in the insulating strips whereby they will be firmly held in insulated relation with respect to each other.

An enlarged sectional view of the manner in which the wires of the resistor are partially embedded in the adjacent insulating surfaces is shown in the Fig. 5. This figure shows a portion 19 of the core upon which the resistance wire 20 is wound; and the adjacent insulating surfaces 21 and 22. A portion of the walls of the external and internal members are shown at 23 and 24 respectively. The radial pressure exerted between the wires and the adjacent insulating surfaces causes part of the insulation to extend between neighboring wires as shown, whereby they are prevented from making contact with one another.

Another method of holding the wires firmly in position is to have only the inner member conical, in which case the maximum radial pressure is exerted on the resistor near its upper edge only.

Referring again to the Fig. 2 the shaft 12 extending through the hollow bushing 9 has fastened to one end the operating knob 13 and the pointer 14. The collar 15 is fastened to the other end of this shaft by means of the set screw 16, and carries the contact arm 17 which bears upon the resistor at its exposed edge.

The operation of the device shown in Figures 1 and 2 is as follows:

An electrical current entering the terminal 7 (Fig. 1) traverses the resistor to the point in contact with the contact arm. It then passes along the contact arm to the shaft and to the metal cups, which are in electrical connection with the terminal 8. In the construction in which the members are made of insulating material, it is necessary to provide a metallic connection from the contact arm to the terminal 8. The rotation of the contact arm 17 by means of the knob 13 obviously varies the resistance between the terminals 7 and 8. The turns of the resistor being firmly embedded in the manner described above will be prevented from moving under the sliding friction of the contact shoe. The resistance wire being separated from the metal cups by only a thin layer of electrical insulation, the heat generated in these wires is readily conducted to these cups and radiated therefrom.

The Fig. 6 shows another structure for achieving the same firm anchorage of the resistance wire. In this figure the moulded insulating base 30 has the resistor 31 mounted about its cylindrical surface. An insulating strip 32 is placed adjacent the turns of the resistor and a metal band 33

is forced over this insulating strip in such a manner as to exert a firm radial pressure thereon. If the moulded base is of a hard unyielding material, it is obviously desirable to also place an insulating strip of 70 slightly yielding material between it and the resistor. This construction serves to hold the wires of the resistor in insulated relation with respect to each other in a manner similar to that described for the 75 Figs. 1 and 2; and also the insulating base provides a convenient mounting for the terminal posts as shown at 34. The metal strip 39 serves to establish electrical connection between the terminal 34 and the movable 80 contact arm 37. The shaft 35, knob 36, and contact arm 37, of this figure are arranged in the manner shown and function in the same way as described for Figs. 1 and 2.

What I claim as new and desire to secure 85 by Letters Patent is:

1. An electrical resistance device comprising a disc with a flanged edge; a second disc with a flanged edge of smaller diameter than said first mentioned disc; and a resistance element held in the annular groove formed by the flanged edges of said discs, and electrically insulated from said discs, and suitable terminals for making electrical connection with said resistance element. 90

2. An electrical resistance device comprising an external cylindrical shell; a resistor circularly disposed within said shell; suitable terminals for said resistor; insulating surfaces adjacent the inner and the outer circumferential surfaces of said resistor; an internal member having a slightly conical circumferential surface, and adapted to be firmly pressed within said resistor, whereby said resistor is subjected to a radial compression and is firmly held between said insulating surfaces. 100

3. An electrical resistance device comprising a cylindrical cup shaped member; a resistor circularly disposed about the inner circumference of said member; suitable terminals for said resistor; a second cylindrical member adapted to fit tightly within said resistor; means for insulating said resistor from said members said means comprising insulating surfaces of slightly yielding character adjacent said resistor; means for drawing and holding said inner member tightly within said resistor whereby a radial compression is exerted upon said resistor and the wire elements thereof are partially embedded in and firmly held by said insulating surfaces. 110

4. An electrical resistance device comprising a cylindrical shell with a conical inner circumferential surface; a resistor disposed within said shell; suitable terminals for said resistor; a second cylindrical member having a conical surface substantially parallel to the inner conical surface of said first men- 120 125 130

- tioned shell; insulating strips adjacent said conical surfaces; and means for firmly pressing said inner member and its associated insulating strip within said resistor, whereby a radial compression is exerted upon said resistor and the wire elements thereof are partially embedded in and firmly held in position by said insulating strips. 5
5. An electrical resistance device comprising a circularly disposed resistor; suitable terminals for said resistor; insulating surfaces adjacent the inner and the outer circumferential surfaces of said resistor; a cylindrical shell within which said resistor is mounted; a second cylindrical member adapted to be firmly pressed inside said resistor whereby said resistor is firmly compressed and held between its adjacent insulating surfaces. 10
- 10 6. An electrical resistance device comprising a plurality of cylindrical shells of varying diameters, co-axially mounted one within the other, a resistance element firmly clamped in the annular groove formed by said cylindrical shells and electrically insulated therefrom, and suitable terminals for establishing electrical connection with said resistance element. 15
- 15 7. An electrical resistance device comprising a cylindrical shell; a resistor mounted within said shell and insulated therefrom; a terminal connected to one end of said resistor; a second cylindrical shell firmly pressed within said resistor and insulated therefrom; a hollow bushing externally threaded and provided with a shoulder and a nut for firmly holding said shells together; a shaft rotatably extending through said bushing; a contact member attached 20 to one end of said shaft and adapted to make a sliding contact with said resistor; an operating knob for rotating said shaft and its associated contact member; and a
- terminal for establishing electrical connection to said contact member. 45
8. An electrical resistance device comprising a circularly disposed resistor; suitable terminals for said resistor; an external band surrounding said resistor and insulated therefrom; an internal cylinder insulated from said resistor and adapted to be firmly pressed into position, whereby said resistor is subjected to a radial compression and the elements thereof are firmly held in place. 50
9. An electrical resistance device comprising a cylindrical insulating base; a resistor mounted on the cylindrical surface of said base; suitable terminals for said resistor; an insulating surface adjacent the outer surface of said resistor; a cylindrical member surrounding said insulating surface and adapted to exert a pressure thereon, whereby the turns of said resistor are partially embedded in said insulating surface and firmly held in insulated relation with respect to one another. 55
10. An electrical resistance device comprising a cylindrical base; a resistor mounted upon the cylindrical surface of said base and insulated therefrom; a terminal for establishing connection to one end of said resistor; a cylindrical band surrounding said resistor, insulated therefrom and adapted to exert a firm radial pressure 60 upon said resistor; a contact arm for establishing a sliding contact on the wire of said resistor; a terminal for establishing electrical connection to said contact arm; and suitable means for rotating said contact arm 65 into a variable position of contact on said resistor. 70
- In witness whereof, I have hereunto subscribed my name.

ERWIN R. STOEKLE.
